DIFFERENTIAL PRESSURE GAUGE

John Vander Horst, Lakewood, Colo., assignor to
Wilkerson Corporation, Englewood, Colo.

Filed June 21, 1971, Ser. No. 155,395

Term of patent 14 years

Int. Cl. D10—04

U.S. Cl. D52—6 R

FIG. 1

FIG. 2

FIG. 3

FIG. 4

FIG. 1 is a front elevational view of a differential pressure gauge showing my new design, the rear elevational view including the dial gauge face being a mirror image thereof except for the latch member;

FIG. 2 is a right side elevational view thereof;

FIG. 3 is a top plan view thereof; and,

FIG. 4 is a bottom view thereof.

I claim:

The ornamental design for a differential pressure gauge, as shown and described.
